US0D1001920S

(12) **United States Design Patent** (10) Patent No.: **US D1,001,920 S**
(45) Date of Patent: ** Oct. 17, 2023

(54) **EXERCISE CYCLE**

(71) Applicant: **Saris Equipment, LLC**, Edison, NJ (US)

(72) Inventors: **Andrew Haala**, Madison, WI (US); **Erik Eagleman**, Madison, WI (US); **Matias Lauryssens**, Madison, WI (US); **Alexander Ingram**, Mount Horeb, WI (US)

(73) Assignee: **SARIS EQUIPMENT, LLC**, Madison, WI (US)

(**) Term: **15 Years**

(21) Appl. No.: **29/838,221**

(22) Filed: **May 11, 2022**

Related U.S. Application Data

(63) Continuation of application No. 16/819,956, filed on Mar. 16, 2020, now Pat. No. 11,400,339, which is a continuation-in-part of application No. 15/999,259, filed on Aug. 16, 2018, now Pat. No. 10,974,118.

(60) Provisional application No. 62/637,003, filed on Mar. 1, 2018, provisional application No. 62/546,728, filed on Aug. 17, 2017.

(57) **CLAIM**

The ornamental design of an exercise cycle, as shown and described.

DESCRIPTION

FIG. 1 is an isometric view of an exercise cycle showing our new design;

FIG. 2 is a second isometric view thereof;

FIG. 3 is a first side elevation view thereof;

FIG. 4 is a second side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line showing of portions of the exercise cycle forms no part of the claim.

1 Claim, 8 Drawing Sheets
